UNITED STATES PATENT OFFICE

105,087

DESIGN FOR A WAFFLE IRON

Walter A. Briegel, Pittsburgh, Pa.

Application November 9, 1936, Serial No. 65,813

Term of patent 14 years

To all whom it may concern:

Be it known that I, Walter A. Briegel, a citizen of the United States of America, residing at Pittsburgh, county of Allegheny, and State of Pennsylvania, have invented a new, original, and ornamental Design for a Waffle Iron, of which the following is a specification, reference being had to the accompanying drawing, wherein:

I claim:

The ornamental design for a waffle iron, as shown.

WALTER A. BRIESEL.
